Primary Examiner — Marianne Pandozzi

(57) **CLAIM**

The ornamental design for an illuminated water bottle dispenser base and piercing tool holder, as shown.

DESCRIPTION

FIG. 1—is a right side perspective view of my illuminated water bottle dispenser base and piercing tool holder showing my new design;

FIG. 2—is a left side perspective view thereof;

FIG. 3—is a left side elevational view thereof;

FIG. 4—is a front elevational view thereof;

FIG. 5—is a right side elevational view thereof;

FIG. 6—is a rear elevational view thereof;

FIG. 7—is a top plan view thereof;

FIG. 8—is a bottom plan view thereof; and,

FIG. 9—is an exploded left side perspective view thereof.

1 Claim, 5 Drawing Sheets
